UNITED STATES PATENT OFFICE.

THOMAS MAYOR, OF PROVIDENCE, RHODE ISLAND.

RING-SPINNING FRAME.

SPECIFICATION forming part of Letters Patent No. 224,344, dated February 10, 1880.

Application filed June 15, 1878.

To all whom it may concern:

Be it known that I, THOMAS MAYOR, of the city and county of Providence, and State of Rhode Island, have invented certain new and useful Improvements in Ring-Spinning Frames; and I hereby declare that the following is a full, clear, and exact description of the same, reference being had to the accompanying drawings, forming part of this specification.

Figure 1 is a front view of a ring-spinning machine in which the ring and ring-rail form a stationary fixture and the bolster and step-rail are made to reciprocate so as to lay the 15 yarn on the bobbin. Fig. 2 is a cross section of part of the machine, showing one ring, spindle, and bobbin, the driving-cylinders and the band for driving the spindles, as also means for reciprocating the spindles. Fig. 3 represents a spindle provided with a long cylindrical whirl.

This invention has reference to improvements in spindles for ring-spinning frames in which the ring and ring-rail are fixed and the 25 spindle is made to reciprocate with the bobbin so as to lay on the yarn; and it consists in the peculiar construction and combination of parts, as will be hereinafter described and claimed.

30 In the drawings, *a a* are two driving-cylinders. *b* is the driving-band. *cc* are the spindles. *dd* are the bobbins. *e* is the stationary ring-rail, and *e'* the stationary ring. *f* is a long cylindrical whirl extending the length of 35 the traverse of the reciprocating spindle, the band on this long whirl adjusting itself as the spindle is slowly reciprocated.

i is the reciprocating bolster-rail, and *k* the reciprocating step-rail. Both of these rails are secured to the posts *l*, so as to reciprocate together. To the step-rails the brackets *m* are secured, provided with anti-friction rolls *m'*, and the step-rail, bolster-rail, and spindles are reciprocated by means of the lever *n*, and the weight counterbalanced by the weight *n'*. Motion is imparted to the rails and spindles by the cam-arm *o* in contact with the rotating heart-cam *p*.

The long cylindrical whirl presents a smooth surface throughout its length for the engagement of the driving-band, which maintains its horizontal position irrespective of the vertical reciprocations of the spindle, and as the belt is not subjected to variable twisting strains, the friction and wear on the same are materially lessened.

Having thus described my invention, I claim as new and desire to secure by Letters Patent—

The combination, in a ring-spinning frame, 60 of a fixed ring-rail, traversing spindle, and traversing step-rail and bolster-rail, a spindle-driving drum working in fixed bearings, and a plain cylindrical spindle-whirl, which is fast on the spindle and the axial length 65 of which is equal, or thereabout, to the length of traverse of the spindle, as and for the purpose herein described.

THOMAS MAYOR.
